CATALYTIC DESULFURIZATION AND
CRACKING OF SULFUR-CONTAIN-
ING PETROLEUMJohn E. Ford, Jr., Garden City, N. Y., assignor to
Houdry Process Corporation, Wilmington, Del.,
a corporation of Delaware

Application June 3, 1947, Serial No. 752,211

7 Claims. (Cl. 196—50)

1

This invention relates to the conversion of hydrocarbon material to useful products and is especially directed to the production of hydrocarbon products, such as engine fuels, fuel oil, kerosene and the like. This invention involves the processing of crude hydrocarbon oils having high sulfur contents, such as sour crude oils, to yield products of commercially acceptable sulfur contents.

Many crude petroleum oils have sufficiently high sulfur content that the various products, such as gasoline or diesel fuel, produced by distillation of the crude oil have sulfur contents that are commercially unacceptable or undesirable and generally must be treated separately, as by expensive chemical methods, to reduce the sulfur content. Chemical methods frequently are useful only to effect a reduction in sulfur content and may cause a substantial reduction in yield of the finished product. Existing catalytic or extraction methods for the reduction of sulfur content involve the considerable expense incident to a separate process. In the case of diesel fuel, prior processes have been either expensive to operate or have resulted in depreciation of this material as a fuel for diesel engines. Indeed, the problem of sulfur content is not confined to fractions having high sulfur contents since many straight run gasolines have a low content of sulfur, such as 0.03 to 0.10 per cent (by weight), which, although low, is sufficient to influence the lead susceptibility and therefore results in an uneconomical use of tetraethyllead.

Moreover, some sulfur-containing crudes have a corrosive effect on the refinery equipment due to the sulfur compounds either originally present or formed during the refining. Such crudes generally but not always fall in the category of crudes having a sulfur content of greater than 1.0 percent by weight of sulfur in the 400° to 1000° F. fraction and will be referred to herein as high sulfur or sour crudes. It should be understood, however, that the types and effect of the sulfur compounds present vary from crude to crude and that, although the above classification is convenient, the present invention includes the processing of crudes which have lower sulfur contents but which behave as sour crudes.

It has now been found, in accordance with the invention, that improvements and economies in the operation of cracking systems employing moving catalysts result by employing freshly regenerated fluent active cracking catalyst of the type described below in two conversion zones, in one of which conversion zones a minor amount of the total freshly regenerated catalyst contacts a normally liquid light straight run fraction of a crude petroleum oil, which light fraction has an objectionable amount of sulfur, under mild conversion conditions and effects desulfurization

2

of the light fraction, and in the other of which conversion zones a major amount of the total freshly regenerated active cracking catalyst contacts a heavy hydrocarbon fraction, such as a gas oil or heavier, under cracking conditions and effects conversion of the heavy fraction to substantial amounts of motor gasoline. The cracking catalyst in each conversion zone passes therethrough in a fluent state and accumulates a coke deposit as a result of the contact with the hydrocarbon material in each zone. Coked catalyst is removed severally from the two conversion zones and regenerated in a single common regeneration zone by oxidizing at least a portion of the coke deposit on the catalyst. Catalyst in a freshly regenerated state is then removed from the regeneration zone and conveyed to the two zones in the proper amounts.

The unitary integrated process described herein furnishes a method whereby a refinery can produce superior motor fuels and other petroleum products from virtually all of the various fractions of a high sulfur crude oil at a low cost. The normally liquid light straight run fraction which is processed in one conversion zone (hereafter called the desulfurization zone for convenience, the other conversion zone being called the cracking zone) to yield products having commercially acceptable sulfur contents may consist of any or all of the straight run or virgin fractions boiling below about 750° F., such as gasoline, kerosene, diesel fuel or light fuel oil, and may conveniently be obtained by a simple distillation from the high sulfur crude oil. It has been unexpectedly found that diesel fuel fractions whose boiling range is approximately within the limits of 400° to 750° F., and which have sulfur contents of greater than 0.5 per cent by weight such as 1.0 to 4.0 per cent, can be desulfurized under the mild conversion conditions described more fully below without substantially depreciating the diesel index or cetane number of the treated fractions while producing, at the same time, as much as 30 per cent of butane-free gasoline (percentages referred to herein are volume percentages unless otherwise designated). Such gasoline has the high octane characteristic of gasoline produced by catalytic cracking under conventional cracking conditions (which are much more severe than the conditions in the desulfurization zone), and is generally above 75 octane number (clear) by the CFR-motor method. The diesel oil fraction may be desulfurized alone or in admixture with straight run gasoline (end boiling point about 400° to 450° F.) obtained from the high sulfur crude oil. Desulfurization of the straight run gasoline from high sulfur crudes (which gasoline generally contains over 0.1 and generally below 0.4 per cent (by weight) of sulfur and is therefore

not marketable or has a poor lead susceptibility or both because of high sulfur content) under the described conditions removes about 60 to 90 per cent of the sulfur originally present to yield a gasoline of high lead susceptibility. Moreover, desulfurization of straight run gasoline of low sulfur content such as 0.02 to 0.09 per cent (by weight) of sulfur, may be effected by the processes herein described, whereby the lead susceptibility and frequently octane number of such gasolines is improved. Such a low sulfur gasoline may be effectively desulfurized either alone or together with diesel fuel cuts from a high sulfur crude oil. When the straight run gasoline from a high sulfur crude oil is desulfurized together with the diesel fuel cut from the same crude, the sulfur content of the final gasoline is slightly higher although the lead susceptibility is not depreciated. In contrast to known methods of operation, the described method of operation of the desulfurization zone considerably increases the amount of gasoline suitable for use in high octane motor fuels with a considerable increase in the octane-barrels of gasoline.

Since a minor amount, preferably less than 25 per cent, of the total catalyst circulating in the system passes through the desulfurization reactor, this reactor is small in comparison to the cracking reactor and the advantages of desulfurizing the light fraction can be gained with only a small increase in the cost of the total equipment and may, in the case of refinery installations presently having cracking and regenerating equipment, be installed at a cost which is very low in comparison to the advantages gained. Thus, in accordance with one embodiment of the invention involving fluent catalysts employed as moving beds in the reactors and in the regenerator, the desulfurization reactor is a part of a unitary plant, which also comprises a relatively large reactor for cracking heavy hydrocarbon stock under conventional cracking conditions for the maximum production of gasoline and a regenerator or kiln for the removal of the coke deposited on the catalyst due to contact with the hydrocarbon material. The catalyst employed is preferably a cracking catalyst of moderate activity as described below, such as a silica-alumina contact mass. After regeneration, the major portion of catalyst is passed through the cracking reactor while a minor portion, preferably less than 25 per cent of the total catalyst leaving the regenerator, is passed to the desulfurization reactor where it contacts a light distillate fraction under mild conversion conditions, and effects desulfurization of the light fraction. By maintaining a low catalyst to oil ratio in the desulfurization reactor (where catalyst to oil ratio is the ratio of the weight of catalyst introduced to the reaction zone per unit time to the weight of oil introduced to the reaction zone per unit time; i. e., pounds of catalyst per pound of oil) a relatively large amount of light distillate is desulfurized without diverting much catalyst from the cracking reactor and thereby avoiding a reduction in the charging rate of oil to the latter.

Passage of the fluent catalyst through the desulfurization reactor as a moving non-turbulent bed has advantages particularly when the light fraction is passed countercurrently therethrough. Under these conditions, the light fraction is charged to the less active portion of the catalyst and the less refractory sulfur compounds are decomposed. As the light fraction progresses up

the catalyst bed, additional sulfur compounds are decomposed until only the more refractory sulfur compounds remain. Such compounds encounter, near and at the top of the bed, the catalyst in a more active state. Also, if the catalyst is introduced at a temperature higher than the average reactor temperature, the catalyst is at a higher temperature. Hence, the refractory sulfur compounds are decomposed near the top of the bed with a minimum of conversion of the remainder of the fraction. Moreover, such counterflow is more efficient in removing heat when the catalyst is charged to desulfurization reactor from the regenerator without intermediate cooling.

It has been found, in accordance with the invention, that a particularly effective mode of operation is to maintain a relatively low catalyst to oil ratio, preferably less than 0.5, but greater than 0.05, such as a ratio in the range of 0.1 to 0.4, in the desulfurization reactor, while maintaining a relatively high ratio, preferably 1.5 or greater, but generally less than 20, such as a ratio in the range between 1.8 and 5.0 in the cracking reactor. When relatively low catalyst to oil ratios, such as 0.1 to 0.4, are maintained in the desulfurization reactor, a large quantity of light fraction can be desulfurized without affecting the throughput of the cracking reactor. Thus, for example, equal amounts of light and heavy fractions can be charged to the desulfurization and cracking reactors while maintaining catalyst to oil ratios of 0.4 and 1.5, respectively, in these reactors, by diverting less than 25 per cent of the total catalyst to the desulfurization reactor. In some cases, the desulfurization reactor may be maintained at a lower temperature than the cracking reactor; the space rate in the desulfurization reactor is generally higher than that in the cracking reactor although approximately the same ranges are useful in both reactors. In the case of existing installations for cracking to which desulfurization reactors are added, essentially the same throughput in barrels per day can be maintained after the addition of the desulfurization reactor as had been maintained before the change by changes in the operating conditions which are within the inherent flexibility of the system.

In order to understand the invention more fully, reference should be had to the drawing which illustrates various embodiments of the present invention, which invention is not, however, limited in scope thereto. These embodiments will be described in connection with operations in which a fluent refractory catalytic contact mass in molded or aggregated form, such as pellets or spheres, is circulated by gravity as a moving, non-turbulent bed through either or both reaction and regeneration vessels. Details of such systems, as applied to cracking operations, have been described in various published articles (see, for example, "The 'T. C. C.' Cracking Process For Motor Gasoline Production" by R. H. Newton, G. S. Dunham and T. P. Simpson, "Transactions Of The American Institute Of Chemical Engineers," volume 41, page 215, April 25, 1945, and the articles there cited) and hence will not be repeated here.

The drawing, in which conventional auxiliary equipment have been omitted for clarity, shows a schematic cracking system illustrating the refining of a crude oil wherein a light fraction is desulfurized and a heavy fraction is cracked.

In the drawing, a catalyst of the type used in cracking operations and discussed more fully below, such as a catalytically active clay, or preferably a low alkali content silica-alumina gel, which has been charged to the system preferably in the form of granules, pellets, or beads of about 3 to 8 mesh and which has been freshly regenerated, is fed by line 2 to hoppers 3 and 4 and thence by lines 5 and 6 to a cracking reactor 7 and a desulfurization reactor 8. A normally liquid light straight run fraction prepared and preheated as described below and having a boiling range below 750° F., is fed by line 9 to desulfurization reactor 8. The light straight run fraction passes upwardly through a downwardly moving bed of catalyst in reactor 8 under the conditions described below and is thereby desulfurized and otherwise subjected to the action of the cracking catalyst. The desulfurized vapors together with the reaction products of desulfurization are removed from the reactor by means of a disengaging section (not shown) and are thence conveyed by line 11 to a fractionator 12 for further processing.

A heavy fraction having an initial boiling point above 400° is introduced to cracking reactor 7 by line 13 preferably in the vapor form. If desired, a fraction principally in the liquid phase may be introduced by line 14 to reactor 7; fractions introduced by lines 13 and 14 being prepared and preheated as described below. Hydrocarbon material introduced by lines 13 and 14 is passed downwardly with a concurrently downwardly moving bed of catalyst. The cracked vapors are removed from the reactor by means of a disengaging section (not shown) and passed by line 15 to a fractionator 16 for further processing.

The downwardly moving beds of catalyst in reactors 7 and 8 are stripped of high boiling hydrocarbonaceous material in standard purging sections (not shown) by means of steam introduced by lines 17 and 18, the purging steam passing upwardly through the bed and merging with the hydrocarbon material treated. Catalyst is removed from reactors 7 and 8 through appropriate draw-off devices and passes by lines 19 and 21 to line 22 where the catalyst streams from the two reactors are merged. The catalyst in line 22 is then conveyed by elevator 23 to line 24 and hopper 25. The catalyst from hopper 25 is charged to a distribution device 26 communicating with a regenerator or kiln 27. Regenerator 27 may be a vessel equipped with a plurality of burning and cooling sections or zones, one of which is indicated in the broken-away section of the regenerator (see article cited above). Air is pumped by pump 28 to preheater 29 to which fuel from line 30 is added. Combustion of the fuel in preheater 29 preheats the air to about 300° F. to 1000° F., which air passes by manifold 32 to lines 33 and thence to the various burning sections of the regenerator in amounts controlled by valves 34. If desired preheater 29 may be by-passed and the air passed directly to the kiln from the pump by line 31. Combustion of the coke is effected by means of the air thus introduced and the spent flue gases so formed are removed by lines 35 to manifold 36, thereafter passing to a flue gas system. The flue gas system may be equipped to recover waste heat and to remove any fine particles of catalyst entrained by the flue gases. The temperature in the regenerator is controlled, at least in part, by indirect heat exchange by means of coils 37 to which

an indirect heat transfer medium, such as water, steam, or a melted mixture of inorganic salts, is fed by lines 38, valves 39 controlling the flow thereof. It is generally preferred to control the amount of air and the amount of heat transfer medium so that the temperature of the catalyst does not rise above a maximum of about 1100° F. The indirect heat transfer medium, after receiving heat in the regenerator, passes by lines 41 to manifold 42 and thence to a heat recovery system 43. The indirect heat transfer medium is cooled in the heat recovery system 43 from which it is removed by line 44 and recirculated to the regenerator by pump 45. Other methods of removing the excess heat in regenerator 27 may be used such as recirculation of a portion of cooled flue gases, recirculation of a portion of cooled catalyst and the like. The catalyst after regeneration by removal of at least a portion of the coke deposit (less than 0.5 per cent by weight of coke preferably being left on the catalyst) is removed from regenerator 27 through an appropriate draw-off device and passes by line 46 to elevator 47 which conveys the catalyst to line 2 for charging in the hoppers 3 and 4.

The amount of catalyst diverted to reactor 8 is, in accordance with the present invention, a minor portion of the total amount of catalyst circulating in the system and is preferably less than 25 per cent and may be as low as 1 to 2 per cent, depending on the amount of light fraction to be desulfurized. As discussed above, when reactor 8 has been added to a pre-existing system, the diversion of such a minor portion of catalyst from the main stream of catalyst passing through reactor 7 furnishes catalyst to the desulfurization reactor while still maintaining, after minor adjustments in the conditions of operation in cracking reactor 7, the same throughput in reactor 7 as was maintained prior to the diversion. In some of such cases, it may be advantageous to increase slightly the speed of elevator 23, this increase, however, being considerably less than sufficient to furnish the entire amount of catalyst employed in reactor 8.

The catalyst in hopper 4 may, if desired, be cooled by a cooling coil 48. However, under some conditions of operation of reactor 8, particularly those in which an average reactor temperature in the range of 800° to 900° is desired, the catalyst may be charged from line 2 without cooling and may enter reactor 8 in the temperature range of 950° to 1050° and be cooled by the light straight run fraction introduced to the reactor so that the average reactor temperature is in the range of 800° to 900°. The light straight run fraction which is introduced into reactor 8 in the vapor form has sufficient heat capacity relative to that of the catalyst, so that the temperature of this fraction is not excessively increased, the increase being generally of the order of less than 100° F., such as 50° F. Such a mode of operation affords excellent control of the desulfurization operation and avoids local overheating of the light fraction with attendant over treatment or cracking. In the latter instance, it is preferred to maintain moderately high space rates (the space rate or space velocity being defined as the volume of liquid hydrocarbon material charged to the reactor per hour referred to the volume of catalyst present in the reactor). Such space rates are preferably in the range of 1.0 to 4.

In general, the conditions of operation of reactor 8 will include average reactor temperatures

in the range of 700° to 900° F., space rates in the range of 0.5 to 5, pressures in the range of atmospheric to slightly above atmospheric, such as 25 pounds per square inch gauge, and catalyst to oil ratios in the range of 0.05 to less than 0.5, and either countercurrent or concurrent flow of catalyst and hydrocarbon material may be employed. However, the combination of operating conditions selected from the above ranges is chosen so as to effect only mild conversion as judged by the amount of lower boiling hydrocarbons produced from the diesel fuel cut. Thus the effect of selecting an operating condition which tends to produce more severe conversion (such as a high temperature, high pressure, low space rate, or high catalyst to oil ratio) is preferably balanced or compensated for by the selection of at least one other operating condition in the opposite sense. It is therefore preferred, in accordance with the present invention, to choose operating conditions so that a gas oil or diesel fuel cut boiling in the range of 400° to 750° undergoes a conversion of less than 35 per cent, with a production of less than about 30 per cent butane-free gasoline and less than 2.0 per cent coke, based on the diesel fuel cut charged. In general, the conditions in reactor 8 are chosen so that the production of coke, based on the weight of light fraction comprising a diesel fuel cut charged to the reactor, is in the range of about 0.5 to 2 per cent and the production of gases lighter than butanes, on the same basis, is about 0.8 to 3.5 per cent by weight. When gasoline alone is treated, the amount of coke is lower, being in the range of about 0.2 to 1.0 per cent while the production of gases lighter than butane is about the same or slightly lower than it is when a diesel fuel cut is charged. Generally, conditions are chosen so that the coke produced in reactor 8 is preferably less than about 15 per cent of the coke produced in reactor 7. When small amounts of catalyst, such as 5 to 10 per cent of the total catalyst, are diverted to reactor 8, the percentage of coke may be higher although it is preferred to choose operating conditions such that less than 2.5 per cent coke is deposited on the catalyst in reactor 8.

The conditions of operation of reactor 1 are well known to the art and lie generally in the ranges of 800° to 1050° F., catalyst to oil ratios between about 1.5 to 20, such as ratios in the range of 1.8 to 5, space rates of 0.5 to 3 and pressures of atmospheric to about 25 pounds per square inch gauge. The cracking operation effected in reactor 1 may be of various types; for example, the hydrocarbon material may be introduced substantially completely in the vapor phase or principally in the liquid phase or in a mixed liquid-vapor phase, and the hydrocarbon material may pass either countercurrently or concurrently through the downwardly moving bed of catalyst. These types of operation are well known to the art and further details need not be repeated here. In general, the cracking conditions will be chosen so that at least 30 per cent, and preferably more than 35 per cent of the material charged to reactor 1 is converted to motor gasoline. Under such conditions the catalyst discharged from the cracking reactor generally will have a carbonaceous deposit of about 1.5 to 3.0 weight per cent based on the catalyst.

Various catalysts, particularly siliceous cracking catalysts, may be employed in the reactors described above. These catalysts are well known to the art and details of their preparation need not be repeated here. Typical of these catalysts

are active or acid activated clays, particularly of the montmorillonite type and synthetic gels comprising silica and at least one other refractory oxide; for example, silica-alumina, silica-alumina-zirconia, silica-zirconia, silica-magnesia, silica-thoria and the like. In accordance with the present invention, it is preferred that such catalysts be prepared or processed so as to yield an active cracking catalyst, such as an activity of above 30 and preferably above 35 measured by the CAT-A test. (The CAT-A test is a commercial test used for the control of the activity of cracking catalysts in which the catalytic activity is expressed as the volume percentage of gasoline referred to the volume of charge stock, produced by cracking a standardized gas oil under standard cracking conditions. Details of this test are given in "Laboratory Method For Determining The Activity Of Cracking Catalysts" by J. Alexander and H. E. Shimp, page R-537, National Petroleum News, August 2, 1944.)

In an embodiment of the present invention involving the processing of sour petroleum crude oils, it is preferred to use in connection therewith a sulfur-resistant catalyst (i. e., a catalyst whose rate of decline of cracking activity is not substantially increased by the presence of sulfur compounds in the hydrocarbon material involved). Synthetic colloidal masses having cracking activity, such as the silica containing gels mentioned above show such resistance in contrast to catalysts prepared by known methods from natural clays. However, sulfur resistant catalysts may be characterized (without regard to source or method of preparation) by the fact that such a catalyst shows substantially no decline in cracking activity, as measured by the "CAT-A" test, when subjected to an accelerated aging test in which the sample of catalyst is subjected to contact with substantially pure hydrogen sulfide at atmospheric pressure at a temperature of 1000° F. for two hours. By the use of sulfur resistant catalysts in accordance with the invention, the equilibrium activity of a fluent catalytic mass circulating through the cracking and desulfurization zones is maintained at a high level, such as above 25 and preferably above 30, as measured by the "CAT-A" test. (The equilibrium activity is the activity of the mass of catalyst circulating in a fluent catalyst system and has a value fixed by a dynamic balance between the effect of adding fresh relatively high activity catalyst to replace catalyst lost or removed and the effect of deterioration of the activity of the catalyst in use.)

In one embodiment of the present invention illustrated by an exemplary operation, 7500 barrels per day of a high sulfur crude oil having sulfur content of about 2 weight per cent and a boiling range (ASTM, Engler) of 100° to 1000° F. are charged by line 51 to fractionator 52 and therein separated into two fractions; about 3400 barrels per day of a light fraction (a wide-cut distillate) having an end point of about 575° to 600° F., although in some instances the end point may be higher, such as up to about 750° F., and about 4100 barrels per day of a heavy fraction comprising the rest of the crude oil. The wide cut distillate is removed as an overhead product through line 53 and the heavy fraction as a bottoms product through line 54. The wide-cut distillate may then be charged to fractionator 55 in which it is separated into a gasoline cut having an end point between 400° and 450° F., which is taken overhead by line 56 and a diesel fuel cut 75 having a boiling range within the limits of 400°

to 750° F. which is removed from the bottom of the fractionator by line 51. Diesel fuel cuts generally have boiling ranges between the 5 per cent and 95 per cent points (ASTM, Engler) of between 50° to 250° F. but such boiling ranges lie within the limits stated. Depending upon the needs of the particular refinery, either the straight run gasoline or the straight run diesel fuel may be sent to storage through lines 58 and 59, respectively, by means of the proper manipulation of valves 61 and 62, or 63 and 64. Alternatively, fractionator 55 may be by-passed by means of proper manipulation of valves 67 and 68 and the overhead from fractionator 52 passed by line 69 directly to line 70 for desulfurization in reactor 8. The charge to the desulfurization reactor, which may consist of all of the material in the crude oil boiling below 750° F., or the straight run diesel fuel, or either the straight run gasoline alone, is passed through heating coil 71 in furnace 72 and thereafter passed by line 9 to reactor 8 as previously described. The treating of straight run gasoline alone is particularly effective when the crude oil has a low sulfur content such as below 1.0 weight per cent. If desired, steam from line 73, preheated to a desired temperature, may be added to the charge to the desulfurization reactor by opening the valve 74, the amount thus added being generally less than 25 weight per cent of the hydrocarbon material charged to the reactor. In the exemplary operation, the entire wide-cut distillate, preheated to a temperature between 750° and 850° F., is charged to the desulfurization reactor which is operated at an average temperature of between 800° and 900° F., freshly regenerated catalyst being introduced to the reactor at a temperature between 900° and 1050° F., and at a rate of about 20 tons per hour. The depth of the catalyst bed is preferably maintained so that the space rate is between 0.8 and 1.5, such as about 1.2. The light fraction, after desulfurization, as described above, is passed by line 11 into fractionator 12 in which it is separated into a low sulfur gasoline, generally below 0.05 per cent, is removed from the fractionator as an overhead fraction by line 75 and thereafter is appropriately stabilized and prepared for marketing by conventional refining methods, such as washing with a solution of caustic. Desulfurized diesel fuel is removed from fractionator 12 by line 76 as a side cut while any material boiling above the diesel range is removed from the bottom of the fractionator by line 77. By means of appropriate manipulation of valves 78 and 79 or 81 and 82, the desulfurized diesel fuel and the bottoms fraction may be sent either to storage or may be included in the charge to the cracking reactor as hereinafter described. In the exemplary operation, about 1900 barrels per day of motor gasoline having a 90 per cent boiling point (ASTM) of 390° F. and 1310 barrels per day of a diesel fuel cut having 10 per cent and 90 per cent boiling points (ASTM) of about 410° and 560° F., respectively, are produced. The motor gasoline so produced has a clear octane number (CFR-motor method) about 6 to 10 points higher than the untreated straight run gasoline; and moreover, the operation increases the amount of gasoline available by 15 to 20 per cent. The operation effectively reduces the sulfur content, that of the gasoline being reduced by about 80 per cent and that of the diesel fuel by about 40 per cent, while the quality of the latter as a diesel engine fuel is substantially unchanged.

The portion of crude which is removed from fractionator 52 by line 54 passes by line 83 to heating coil 84 and a furnace 85 in which it is heated to a temperature in the range of 800° to 900° F. In addition to the portion of the crude boiling above the wide cut distillate, the material in line 83 may also include material desulfurized in reactor 8, such as all or a portion of the desulfurized diesel fuel introduced by lines 86 and 87 to line 83, or it may include the bottoms fraction from the material desulfurized in reactor 8 introduced by lines 77 and 87 to line 83, or it may contain an untreated diesel fuel or gas oil cut introduced by lines 57, 88 and 87 or it may contain a recycle gas oil cut introduced by lines 90 and 87 to line 83. Thus, for example, the hydrocarbon material in line 83 may comprise 4100 barrels per day of the bottoms fraction from fractionator 52, 510 barrels per day of hydrocarbon material from the fractionator 12 and 5310 barrels per day of a heavy gas oil in line 90, which gas oil is obtained from the products of cracking in reactor 7. In order to aid in the subsequent volatilization of the material in line 83 and to prevent coking in the furnace, steam may be added to the material in line 83 through line 89 by opening valve 91. The hydrocarbon material in line 83 after passage through furnace 85 is charged through line 92 to a tar separator 93 from which a vaporized overhead fraction is removed by line 94 and an unvaporized liquid fraction removed by line 95, which fraction may, for example, be about 23 per cent of the charge introduced by line 92. The unvaporized liquid fraction may be directed to storage through line 96 by opening valve 97 or it may be directed to a deasphaltizing zone 98 by opening valve 99 and passing it through line 101. In deasphaltizing zone 98 which may employ propane deasphaltizing or vacuum distillation to remove the heavy asphaltic material, the material from line 101 is separated into catalytic cracking stock which is removed from the deasphaltizing zone 98 by line 102 and the asphaltic fraction which is removed from this zone by line 103. When propane deasphaltizing is used, as in the exemplary operation, the conditions of deasphaltizing are selected to produce 1370 barrels per day of a clean charge stock having an end point of about 1100° F. The overhead fraction from the tar separator in line 94 and the deasphaltized cracking stock in line 102 are passed through heating coils 104 and 105 in furnace 106 and thence charged to reactor 7 by lines 13 and 14. The hydrocarbon material cracked in reactor 7 under the conditions described above is fractionated by fractionator 16 so as to produce a cracked gasoline fraction amounting, in the exemplary operation, to about 35 to 70 volume per cent of the fresh oil feed introduced to reactor 7. The gasoline from the fractionator in line 107 is thereafter appropriately processed such as by stabilization and removal of fixed gases and by washing with a solution of caustic. A light gas oil fraction is removed from fractionator 16 by line 110, a heavy gas oil fraction by line 108 and a bottoms fraction by line 109. The heavy gas oil fraction may, if desired, be recycled to the cracking reactor 7 by means of lines 90 and 87, valves 111 and 112 being appropriately manipulated.

In order to illustrate the present invention but not to be construed as a limitation thereof, the following specific examples are given:

11
EXAMPLE I

A Wyoming crude oil (about 60% Elk Basin and 40% Frannie) was distilled to produce a wide cut distillate as a light fraction. The remainder of the crude was separated into an overhead fraction and tarry bottoms in a tar separator, the tarry bottoms deasphaltized using propane, and the deasphaltized material combined with the tar separator overhead to yield a heavy fraction for cracking. The properties of the crude oil and liquid fractions were as follows:

TABLE IA

	Crude Oil	Light Fraction	Heavy Fraction
Gravity, °API	28.5	47.8	21.5
Volume percent of crude	100	45.4	42.9
Distillation—ASTM:			
Initial, °F.	146	120	1617
10%.....	290	165	1668

¹ Vacuum distillation corrected to atmospheric pressure.

The light fraction and the heavy fraction were separately charged to reactors containing moving beds of freshly regenerated active cracking catalyst having less than 0.2 weight per cent of residual carbon thereon. The catalyst used was in the form of beads of calcined synthetic low alkali silica-alumina hydrogel prepared in a manner known to the art and having a "CAT-A" activity index of about 33. The light fraction was charged to the bottom of a desulfurization reactor in counter-current relationship to the moving bed of catalyst; the heavy fraction being charged to the cracking reactor in mixed phase condition at the top of the catalyst bed for concurrent flow with the moving bed of catalyst. The temperature of the catalyst charged to the desulfurization reactor was about 755° F., which is approximately 220° F. lower than the average temperature of the catalyst following regeneration and represents a removal of 110,000 B. t. u. per ton of catalyst by cooling. The conditions of operation are given in the following table:

TABLE IB

Operation.....	Desulfurization		Cracking
	Light Fraction	Heavy Fraction	
Space rate, total charge.....	1.2	1.21	
Fresh feed.....		0.50	
Recycle gas oil.....		0.71	
Catalyst to oil ratio, based on total charge.....	0.4	1.53

Coke deposited on catalyst, weight per cent based on catalyst.....	1.0	3.0	
C ₃ and lighter, weight per cent of total oil charged.....	0.9		
Coke, weight per cent of total oil charged.....	0.4		
Liquid recovery, volume per cent of charge.....	102.2	94.0	

Catalyst was removed from the desulfurization reactor and from the cracking reactor and regeneration effected in the type of regenerator

referred to above, under conditions such that the residual coke was less than 0.2 weight per cent; the catalyst being thus rendered suitable for reuse in the desulfurization and cracking reactors.

The products from the desulfurization and cracking reactors were fractionated separately; the yields and properties being given below. The properties of the straight run gasoline present in the untreated light fraction are given for comparison.

¹ Washed with a solution of caustic.

By operating the desulfurization and cracking reactors in conjunction with a single regenerator under the above conditions, the catalyst from the desulfurization reactor, which is only about 7% of the total catalyst, adds only 2.6% to the total amount of coke burned, and, although 130° F. cooler than the catalyst from the cracking reactor, lowers the temperature of the latter only 10° F. when admixed therewith.

The gasoline from the desulfurization and cracking operations, when blended in amounts proportional to the relative amounts of the charges in the crude oil and with the addition of 3 cc. TEL, yield a gasoline having about 83.0 CFR-M and 89. CFR-R. A gasoline blended in

a similar manner from the untreated straight run gasoline described in Table IC and the catalytically cracked gasoline has an octane number of 78.3 CFR-M and 85.6 CFR-R.

EXAMPLE II

Crude oil from the Slaughter field (West Texas) was distilled to produce the fractions having the following properties:

TABLE II A

Properties	Light Fraction	Heavy Fraction
Gravity, °API	52.5	25.5
Boiling range, ASTM °F	120 to 422	469 to 1000
Sulfur, weight per cent	0.36	2.36
Octane number:		
CFR-M, clear	50.9	
+ 3 cc. TEL	63.2	
Yield, volume per cent	34.5	48.9

The light fraction was desulfurized and the heavy fraction cracked in a similar manner, including type and activity of catalyst, to that described in connection with Example I except the temperature of the catalyst charged to both operations was in the range of 940° to 975° F. (approximately the exit temperature of the regenerator) and the light fraction was passed through the reactor in concurrent relationship to the moving bed of catalyst. The conditions of the operations were as follows:

TABLE II B

Operation	Desulfurization	Cracking
Charge	Light Fraction	Heavy fraction
Space rate, total charge	1.6	2.34
Fresh feed		0.77
Recycle gas oil		1.57
Catalyst to oil ratio based on total charge	0.41	2.08
Temperatures, °F.:		
Catalyst inlet	940 to 975	940 to 975
Oil inlet	850	895
Average of reactor	845	905
Catalyst outlet	840	895
Pressure, pounds per sq. in.	10	
Catalyst circulation tons/hour through reactor ¹	8.5	250
Coke deposited on catalyst, weight per cent based on catalyst	0.47	2.23
C ₃ and lighter, weight per cent oil charged	1.5	

¹ Based on a crude oil charge of 12,000 barrels per day.

As in the previous example, regeneration of the catalyst removed from the desulfurization and from the cracking zones was effected in a regenerator whose temperatures were controlled by indirect heat transfer. In the present case, mixture of the two streams of catalyst from the desulfurization and cracking zones results in virtually no change in the temperature of the catalyst from the cracking zone (less than 2° F.) and the coke on the catalyst from the desulfurization zone adds less than 1% to the total amount of coke burned in the regenerator.

The desulfurized light fraction was distilled to yield 94 volume per cent of debutanized motor gasoline, having a boiling range of 140° to 408° F. and an unleaded octane number (CFR-M) of 56.2 and an octane number of 74.5 with 3 cc. TEL. The synthetic crude from the cracking operation yielded, on distillation, about 60.5 volume per cent of motor gasoline and 10.5 volume per cent of fuel oil (based on the amount of fresh oil charged to the reactor), the motor gasoline having an octane number (CFR-M) of 81 (clear)

and 85.6 (with 3 cc. TEL). A motor gasoline blended from the desulfurized and cracked products in the relative proportions in which they were produced has an octane number (CFR-M) of 81.2 (with 3 cc. TEL) in contrast to a blend of untreated and cracked gasoline blended on the same basis which has an octane number (CFR-M) of 76.8 (with 3 cc. TEL).

EXAMPLE III

A diesel fuel cut was prepared from the crude oil of Example II by distillation and had the following properties:

TABLE III A

15	Gravity, °API	32.3
	Boiling range, ASTM °F	464 to 656
	Sulfur, weight percent	1.43
	Aniline point, °F	140
20	Diesel index	45.2
	Cetane number	48.6

The above cut was contacted in a pilot plant with catalyst of the type described in Example I in an operation equivalent to the following conditions in a commercial size moving bed reactor:

TABLE III B

30	Space velocity	2.0
	Catalyst to oil ratio	0.32
	Temperatures, °F.:	
	Catalyst inlet (estimated)	970
	Oil inlet	855
	Average of reactor	840
	Catalyst outlet	830

35	Catalyst circulation, tons/hour ¹	5
	Coke deposited on catalyst, weight percent based on catalyst	2.4
	C ₃ and lighter, weight percent of oil charged	1.8
	Coke formed, weight percent of oil charged	0.9

40	¹ Based on 12,000 barrels of crude oil charged per day.	
	The operation produced a synthetic crude which, when distilled, yielded 22.5 volume percent (based on original cut) of motor gasoline having an octane number (CFR-M) of 78.8 (clear) and 83.3 (with 3 cc. TEL) and 74.5 volume percent (based on original diesel cut) of desulfurized diesel fuel having the following properties:	
	Catalyst inlet (estimated)	970
	Oil inlet	855
	Average of reactor	840
	Catalyst outlet	830

TABLE III C

50	Gravity, °API	32.6
	Boiling range, ASTM °F	460 to 680
	Sulfur, weight percent	1.09
	Aniline point, °F	143
	Diesel index	46.6
55	Cetane number	49.6

55	When the commercial size desulfurization reactor referred to above is operated in conjunction with a cracking reactor as described in Example II, there is produced not only a desulfurized diesel fuel fraction of as good engine quality as the virgin fraction, but also a quantity of high octane gasoline which considerably augments that produced in the cracking reactor.	
	In the specification, the fraction boiling between 400° and 750° F. has, for convenience and brevity, been referred to a diesel fuel fraction. It is to be understood, however, that this fraction may be used for other purposes where its composition and boiling range are suitable. Thus all or a part of the 400° to 750° F. fraction may be used as a tractor fuel, fuel for jet engines and gas turbines, a burning distillate or kerosene, a high grade fuel oil and the like.	
65		
70		

Obviously many modifications and variations of the invention as hereinbefore set forth may be

made without departing from the spirit and scope thereof and therefore only such limitations should be imposed as are indicated in the appended claims.

I claim as my invention:

1. The process of refining a crude petroleum oil having a sulfur content of 1 per cent by weight or greater in the 400° to 1000° F. fraction which comprises fractionating said crude into a light distillate consisting of motor gasoline and diesel fuel and a heavy residual fraction, removing the asphaltic portion from said heavy fraction, passing said light distillate through a first conversion zone, introducing freshly regenerated fluent active cracking catalyst to said first conversion zone, maintaining mild conversion conditions in said first conversion zone such that the coke produced from said light distillate is in the range of 0.5 to 2.0 per cent by weight and the amount of gas lighter than butanes produced from said light distillate is in the range of 0.8 to 3.5 per cent by weight, passing the deasphaltized heavy fraction through a second conversion zone, introducing freshly regenerated fluent active cracking catalyst to said second conversion zone in an amount substantially greater than the amount introduced to said first conversion zone, maintaining cracking conditions in said second conversion zone so as to effect cracking of said heavy fraction to at least 35 per cent of motor gasoline based on the amount of fresh feed to said zone; removing coked catalyst from said first and second conversion zones, regenerating a mixture of coked catalyst from the first and second conversion zones in a regeneration zone adapted to remove excess heat by indirect heat transfer, removing freshly regenerated catalyst from said regeneration zone, returning freshly regenerated catalyst to said first and second conversion zones, separating the products from said first conversion zone into gasoline and diesel fuel fractions, separating the products from said second conversion zone into gasoline and other fractions, and blending the gasoline fractions from the first and second conversion zones to yield a gasoline of high lead susceptibility.

2. The process of claim 1 in which the amount of catalyst passed through said first conversion zone is less than 25 per cent of the total catalyst regenerated.

3. The process of claim 1 in which the amount of catalyst passed through said first conversion zone is less than 10 per cent of the total catalyst regenerated.

4. The process of claim 1 in which the fluent catalyst moves through the two conversion zones and through the regeneration zone as moving non-turbulent beds.

5. The process of refining a crude petroleum oil having a sulfur content of 1 percent by weight or greater in the 400° to 1000° F. fraction which comprises fractionating said crude into a light distillate consisting of motor gasoline and diesel fuel and having an end point below about 750° F. and a heavy fraction comprising the remainder of said crude, heating said heavy fraction to a temperature in the range of 800 to 900° F. and separating said heavy fraction into a vaporous fraction and an asphalt containing liquid fraction, removing asphalt from said liquid fraction, passing said light distillate through a downwardly moving non-turbulent bed of catalyst in a first conversion zone, introducing freshly regenerated fluent active cracking catalyst to said first conversion zone in amounts such that a cata-

lyst to oil ratio of less than 0.5 and greater than 0.05 is produced, maintaining mild conversion conditions in said first conversion zone such that the coke produced from said light distillate is in the range of 0.5 to 2.0 percent by weight and the amount of gas lighter than butanes produced from said light distillate is in the range of 0.8 to 3.5 percent by weight, passing the deasphaltized liquid fraction and said vaporous fraction through a downwardly moving non-turbulent bed of catalyst in a second conversion zone, introducing freshly regenerated fluent active cracking catalyst to said second conversion zone in amounts such that a catalyst to oil ratio of greater than 1.5 is produced, maintaining cracking conditions in said second conversion zone so as to effect cracking of the total hydrocarbons charged to at least 35 percent of motor gasoline, removing coked catalyst from said first and second conversion zones, regenerating a mixture of coked catalyst from the first and second conversion zones in a regeneration zone adapted to remove excess heat by indirect heat transfer, removing freshly regenerated catalyst from said regeneration zone, returning freshly regenerated catalyst to said first and second conversion zones, separating gasoline and diesel fuel from the products from said first conversion zone, said diesel fuel having substantially the same diesel index as that of the straight run untreated diesel fuel and having a substantially lower sulfur content than said untreated diesel fuel, separating gasoline from the products from said second conversion zone, and blending the gasoline fractions from the first and second conversion zones to yield a gasoline of high lead susceptibility.

6. The process of refining a crude petroleum oil having a sulfur content of 1 percent by weight or greater in the 400° to 1000° F. fraction which comprises separating said crude into a light distillate comprising diesel fuel and having an end point below about 750° F. and a heavy residual fraction, deasphalting said heavy residual fraction, passing said light distillate through a downwardly moving non-turbulent bed of catalyst in a first conversion zone, introducing freshly regenerated fluent active cracking catalyst to said first conversion zone in amounts such that a catalyst to oil ratio of less than 0.5 and greater than 0.05 is produced, maintaining mild conversion conditions in said first conversion zone such that the coke produced from said light distillate is in the range of 0.5 to 2.0 percent by weight and the amount of gas lighter than butanes produced from said light distillate is in the range of 0.8 to 3.5 percent by weight, passing the deasphalted heavy residual fraction through a downwardly moving non-turbulent bed of catalyst in a second conversion zone, introducing freshly regenerated fluent active cracking catalyst to said second conversion zone in amounts such that a catalyst to oil ratio of greater than 1.5 is produced, maintaining cracking conditions in said second conversion zone so as to effect cracking of the total hydrocarbons charged to at least 35 percent of motor gasoline, removing coked catalyst from said first and second conversion zones, regenerating a mixture of coked catalyst from the first and second conversion zones in a common regeneration zone, removing freshly regenerated catalyst from said regeneration zone, returning freshly regenerated catalyst to said first and second conversion zones, separating gasoline and diesel fuel from the products from said first conversion zone, said diesel

fuel having substantially the same diesel index as that of the straight run untreated diesel fuel and having a substantially lower sulfur content than said untreated diesel fuel, separating gasoline from the products from said second conversion zone, and blending the gasoline fractions from the first and second conversion zones to yield a gasoline of high lead susceptibility.

7. The process of refining a crude petroleum oil having a sulfur content of 1 percent by weight or greater in the 400° to 1000° F. fraction which comprises fractionating said crude into a light distillate comprising diesel fuel and having an end point below about 750° F. and a heavy fraction comprising the remainder of said crude, separating said heavy fraction into a vaporous fraction and an asphalt containing liquid fraction, removing asphalt from said liquid fraction, passing said light distillate through a downwardly moving non-turbulent bed of catalyst in a first conversion zone, introducing freshly regenerated fluent active cracking catalyst to said first conversion zone in amounts such that a catalyst to oil ratio of less than 0.5 and greater than 0.05 is produced, maintaining mild conversion conditions in said first conversion zone such that the coke produced from said light distillate is in the range of 0.5 to 2.0 percent by weight and the amount of gas lighter than butanes produced from said light distillate is in the range of 0.8 to 3.5 percent by weight, passing the deasphalted liquid fraction and said vaporous fraction through a downwardly moving non-turbulent bed of catalyst in a second conversion zone, introducing freshly regenerated fluent active cracking catalyst to said second conversion zone in amounts such that a catalyst to oil ratio of greater than 1.5 is produced, maintaining cracking conditions in said second conversion zone so as to effect cracking of the total hydrocarbons charged to at least 35 percent of motor gasoline, removing coked catalyst from said first and second conversion zones, regenerating a mixture of

coked catalyst from the first and second conversion zones in a common regeneration zone, removing freshly regenerated catalyst from said regeneration zone, returning freshly regenerated catalyst to said first and second conversion zones, separating gasoline and diesel fuel from the products from said first conversion zone, said diesel fuel having substantially the same diesel index as that of the straight run untreated diesel fuel and having a substantially lower sulfur content than said untreated diesel fuel, separating gasoline from the products from said second conversion zone, and blending the gasoline fractions from the first and second conversion zones to yield a gasoline of high lead susceptibility.
